(57) **CLAIM**

We claim the ornamental design for a plant irrigator, as shown and described.

DESCRIPTION

FIG. 1 is a perspective view of a plant irrigator; FIG. 2 is a side view thereof, the opposite side being identical; FIG. 3 is a front view thereof, the rear being identical; FIG. 4 is a top view thereof; and, FIG. 5 is a bottom view thereof.

The broken lines are included for purposes of illustration and form no part of the claimed design.

1 Claim, 2 Drawing Sheets
